UNITED STATES PATENT OFFICE.

EDWIN E. HILLIKER, OF EAST AURORA, NEW YORK.

LIQUID-FUEL BURNER.

1,347,858.

Specification of Letters Patent. Patented July 27, 1920.

Application filed August 29, 1918, Serial No. 251,881. Renewed June 8, 1920. Serial No. 387,513.

To all whom it may concern:

Be it known that I, EDWIN E. HILLIKER, a citizen of the United States, residing in East Aurora, in the county of Erie and

5 State of New York, have invented new and useful Improvements in Liquid-Fuel Burners, of which the following is a specification.

This invention relates to a liquid fuel burner which is more particularly designed 10 for producing heat in a stove by the use of kerosene oil although the same may also be used for other heating purposes and in connection with other kinds of liquid fuel.

It is the object of this invention to produce a burner of this character which is 15 very simple in construction, capable of being produced at low cost, not liable to get out of order, readily inspected, cleaned or repaired and one which will produce a 20 maximum heating effect for the amount of fuel consumed and not liable to back fire or interfere with the proper burning of the combustible mixture after the same has burned for some time.

25 In the accompanying drawings:

Figure 1 is a side elevation of the liquid fuel burner embodying my improvements. Fig. 2 is a sectional top plan view thereof with the top plate or cover removed. Fig. 3 30 is a vertical longitudinal section taken on line 3—3, Fig. 2. Fig. 4 is a vertical cross section of the same taken on line 4—4, Fig. 2.

Similar characters of reference refer to 35 like parts throughout the several views.

In its general organization this burner comprises a longitudinal mixing chamber 1 into the front or outer end of which the vaporized liquid and air are introduced so 40 as to become mixed in this chamber, two longitudinal delivery chambers 2, 2, arranged on opposite sides of the mixing chamber and having their corresponding rear ends connected with the rear end of 45 the mixing chamber, two burning surfaces 3, 3, arranged on the outer longitudinal sides of the delivery chamber, and a heating coil 4 preferably of U-shape which has one leg arranged adjacent to the burning 50 surface of one delivery chamber and another leg arranged adjacent to the other delivery chamber, one end of this pipe having a supply-controlling valve 5 and connected with a liquid supply such as a kerosene oil tank while the opposite end of this 55

pipe is provided with a delivery valve 6 through which the heated liquid is discharged into the outer or inlet end of the mixing chamber.

In carrying the chambers of this invention into practical form the same are preferably constructed as follows:

7 represents a horizontal bottom plate or floor provided on its upper side with two longitudinal inner walls 8, 8 which are arranged parallel but spaced apart and which have their front ends in line with the front or outer end of the bottom plate while their inner or rear ends terminate short from the rear end of the bottom plate, two longitudinal outer walls 9, 9 arranged along opposite longitudinal edges of the bottom plate, a curved rear wall 10 arranged along the curved rear end of the bottom plate, and two transverse walls 11, 11 each of which is arranged at the front end of the bottom plate and connects the corresponding front ends of one inner longitudinal wall and one outer longitudinal wall, said bottom plate and said walls being preferably constructed 80 integrally of cast iron.

12 represents a top plate or cover which extends over the upper edges of the walls and is provided on its underside with grooves or channels 13 which receive the upper edges of these walls so as to form a comparatively tight joint therewith. This cover or top plate may be connected with the bottom plate and associated parts in any suitable manner, for instance, by means of 90 screws 14 bearing with their headed ends against the outer side of the top plate while their threaded ends engage with correspondingly threaded openings in the bottom plate, as best shown in Fig. 3. By this 95 means the inlet or mixing chamber is formed between the inner longitudinal walls and the adjacent parts of the top plate and bottom plate and each of the delivery or outlet chambers is formed between one 100 of the inner longitudinal walls and the companion outer longitudinal walls and the adjacent parts of the top and bottom plates.

Each of the delivery chambers is provided with a longitudinal burner opening 105 15 arranged in the outer longitudinal wall of this chamber and extending to the top plate so that the latter serves to complete the burner opening for the respective delivery chamber. The burning surface in 110

this burner opening is preferably constructed in the form of a screen which is held in place by engaging its lower horizontal edge with a lower channel or groove 16 formed in the lower edge of the burner opening, two upright grooves 17, 17 formed in the upright edges of this burner opening, and an upper groove 18 formed horizontally in the adjacent longitudinal edge 10 portion of the top plate. By this means the screen forming the burning surface can be easily put in place when assembling the parts as well as readily removed therefrom when worn out and replaced by another, so 15 that it is possible to maintain the burner conveniently in its best working condition.

The U-shaped heating pipe is preferably so mounted on the outer side of the delivery chambers that the same is readily detachable therefrom, for which purpose a plurality of pairs of retaining lugs 19, 19 are provided the members of each pair being arranged one above the other, and one pair being arranged at the front ends of the 25 longitudinal outer walls and another pair centrally on the outer side of the curved rear wall. The U-shaped heating pipe is preferably so constructed that in order to engage its legs and curved bow with the 30 pairs of retaining lugs on the outer longitudinal walls and the curved rear wall, it is necessary to spring the legs of this heating pipe apart somewhat, and after the bow and legs of this pipe have been engaged 35 with the several pairs of retaining lugs, as shown in the drawings, the resilience of this pipe operates to hold the same reliably in place without requiring any additional fastening means, thereby reducing the cost of 40 manufacture accordingly and materially simplifying the construction. The legs of the heating pipe are preferably arranged lengthwise along the outer sides of the outer longitudinal walls so that the tops 45 of these legs are adjacent to the lower edges of the burner openings and burning surfaces, whereby the flames upon issuing from these burning surfaces will play against the upper sides of these heating 50 pipe legs and heat the contents thereof.

It follows from this construction, that when kerosene oil or other liquid hydrocarbon or fuel is supplied through the inlet end of the heating pipe, that the same 55 passes successively through the legs of the heating coil and is exposed to the flames issuing from the burning surface whereby this liquid is raised in temperature and caused to issue from the delivery valve 60 in a vapor condition. This vapor is delivered into the front or inlet end of the mixing chamber and carries with it a continuous stream of air into the mixing chamber. This liquid fuel and air during their passage 65 through the mixing chamber become

thoroughly commingled, so as to form a combustible mixture in which all parts are thoroughly mixed and in the best condition for subsequent combustion. Upon reaching the rear end of the mixing chamber this 70 combustible mixture strikes the curved rear wall and is divided into two streams which are caused to travel in a direction opposite to that in which the mixture moves through the mixing chamber, one of these streams 75 passing reversely and forwardly through one of the delivery chambers and the other reversely and forwardly through the other delivery chamber. As the mixture in each delivery chamber reaches the outlet opening 80 of the latter, the same issues in the form of a finely divided body through the screen therein and burns on the outer side of the latter which forms the burning surface. The flames issuing from these burning surfaces 85 pass upwardly as well as laterally for heating any object which may be above or at the side of the burner, and part of these flames are engaged with or are sufficiently close to the upper sides of the heating pipe 90 legs to vaporize the kerosene oil within the latter.

By this means a thorough preheating or vaporization of the kerosene oil or other liquid fuel is effected before it is delivered into the mixing chamber, a large and ample volume of air is drawn into the mixing chamber with the vaporized fuel, and a free outlet for the combustible mixture is formed on opposite longitudinal sides of the 100 burner so as to furnish the maximum heat for the quantity of fuel which is consumed.

Owing to the flames of this burner being on opposite longitudinal sides thereof and fresh air being continuously drawn through 105 the central part of the same, there is a constant tendency to keep the central part of the burner cool, so that overheating of the same and backfiring which would follow such overheating, is prevented.

Furthermore, this burner is very compact and simple in construction, it has comparatively few parts, most of which can be cast of metal at low cost without requiring any 110 coring or expensive machine work for fitting them together. Moreover, by arranging the heating coil so that the same is only exposed to a part of the flames, it is possible to obtain the requisite vaporization of the liquid without unduly heating this pipe 120 which otherwise would cause the same to be burned out and necessitate frequent renewal.

I claim as my invention:

1. A liquid fuel burner comprising a longitudinal mixing chamber having an inlet 125 for liquid fuel and air at one end, two delivery chambers arranged lengthwise on opposite sides of the mixing chamber and communicating at their corresponding ends with 130

- the opposite end of the mixing chamber and causing the combustible mixture as it issues from said mixing chamber to divide and move through said delivery chambers in an 5 opposite direction from the path of movement through said mixing chamber, and each of said delivery chambers being provided on its outer longitudinal side with a burning surface, and a U-shaped heating 10 pipe arranged around the mixing and delivery chambers and having parts arranged adjacent to said burning surfaces and having an outlet opening toward said inlet of the mixing chamber.
- 15 2. A liquid fuel burner comprising a bottom plate, two inner longitudinal walls arranged between the opposite longitudinal edges of said bottom plate and extending with their outer ends from one end of the 20 latter but terminating with their inner ends short of the opposite end of the same, two outer longitudinal walls arranged along the opposite longitudinal edges of said bottom plate, a curved end wall arranged on the 25 bottom plate opposite the inner ends of said inner walls and connecting the adjacent ends of the outer longitudinal walls, two transverse end walls arranged on the bottom plate and each connecting the outer end of one of said inner longitudinal walls with the corresponding end of one of said outer longitudinal walls, and a top plate engaging the upper edges of said walls and forming with 30 said walls and bottom a mixing chamber 80 between said inner longitudinal walls and two delivery chambers between said inner and outer longitudinal walls, each of said outer longitudinal walls being provided with a longitudinal burner opening extending to 85 said top plate, a burner screen arranged in each of said burner openings, said bottom plate and walls being formed integrally and screws connecting said bottom and top plates. 90
5. A liquid fuel burner comprising a bottom plate, two inner longitudinal walls arranged between the opposite longitudinal edges of said bottom plate and extending with their outer ends from one end of the 40 latter but terminating with their inner ends short of the opposite end of the same, two outer longitudinal walls arranged along the opposite longitudinal edges of said bottom plate, a curved end wall arranged on the 45 bottom plate opposite the inner ends of said inner walls and connecting the adjacent ends of the outer longitudinal walls, two transverse end walls arranged on the bottom plate and each connecting the outer end of one of said inner longitudinal walls with the corresponding end of one of said outer longitudinal walls, and a top plate engaging the upper edges of said walls, and forming with 50 said walls and bottom a mixing chamber 100 between said inner longitudinal walls and two delivery chambers between said inner and outer longitudinal walls, each of said outer longitudinal walls being provided with a longitudinal burner opening 105 extending to said top plate, said bottom plate and walls being formed integrally and said top plate being provided on its underside with grooves which receive the upper edges of said walls. 110
6. A liquid fuel burner comprising a bottom plate, two inner longitudinal walls arranged between the opposite longitudinal edges of said bottom plate and extending with their outer ends from one end of the 55 latter but terminating with their inner ends short of the opposite end of the same, two outer longitudinal walls arranged along the opposite longitudinal edges of said bottom plate, a curved end wall arranged on the 60 bottom plate opposite the inner ends of said inner walls and connecting the adjacent ends of the outer longitudinal walls, two transverse end walls arranged on the bottom plate and each connecting the outer end of one of said inner longitudinal walls with the corresponding end of one of said outer longitudinal walls, and a top plate engaging the upper edges of said walls, and forming with 65 said walls and bottom a mixing chamber 115 between said inner longitudinal walls and two delivery chambers between said inner and outer longitudinal walls, each of said outer longitudinal walls being provided with a longitudinal burner opening 120 extending to said top plate, said bottom plate and walls being formed integrally and said top plate being provided on its underside with grooves which receive the upper edges of said walls. 125
4. A liquid fuel burner comprising a bottom plate, two inner longitudinal walls arranged between the opposite longitudinal edges of said bottom plate and extending with their outer ends from one end of the 70 latter but terminating with their inner ends short of the opposite end of the same, two outer longitudinal walls arranged along the opposite longitudinal edges of said bottom plate, a curved end wall arranged on the 75 bottom plate opposite the inner ends of said inner walls and connecting the adjacent ends of the outer longitudinal walls, two transverse end walls arranged on the bottom plate and each connecting the outer end of one of said inner longitudinal walls with the corresponding end of one of said outer longitudinal walls, a top plate engaging the upper edges of said walls and forming with 80 said walls and bottom a mixing chamber 85 between said inner longitudinal walls and two delivery chambers between said inner and outer longitudinal walls, each of said outer longitudinal walls being provided with a longitudinal burner opening 90 extending to said top plate, a burner screen arranged in each of said burner openings, said bottom plate and walls being formed integrally and screws connecting said bottom and top plates. 130

- bottom plate opposite the inner ends of said inner walls and connecting the adjacent ends of the outer longitudinal walls, two transverse end walls arranged on the bottom plate and each connecting the outer end of one of said inner longitudinal walls with the corresponding end of one of said outer longitudinal walls, a top plate engaging the upper edges of said walls and forming with said walls and bottom a mixing chamber between said inner longitudinal walls and two delivery chambers between said inner and outer longitudinal walls, each of said outer longitudinal walls being provided with a longitudinal burner opening extending to said top plate, the edges of said burner opening and the adjacent part of the top plate being provided with grooves, and burner screens for said burner openings each screen engaging its edges with the grooves in the edges of said burner opening and top plate.

7. A liquid fuel burner comprising a longitudinal mixing chamber having an in-

let for liquid fuel and air at one end, two delivery chambers arranged lengthwise on opposite sides of the mixing chamber and communicating at their corresponding ends with the opposite end of the mixing chamber and causing the combustible mixture as it issues from said mixing chamber to divide and move through said delivery chambers in an opposite direction from the path of movement through said mixing chamber and each of said delivery chambers being provided on its outer longitudinal side with a burning surface, a U-shaped heating pipe arranged around mixing and delivery chambers and having parts arranged adjacent to said burning surfaces and having an outlet opening toward said inlet of the mixing chamber, and pairs of retaining lugs arranged on the exterior of said outer longitudinal and curved end walls and each pair receiving a part of said heating pipe between its members.

EDWIN E. HILLIKER.
